WATCH PROTECTOR

Samuel Fass, Brooklyn, N. Y.

Application March 30, 1950, Serial No. 8,862

Term of patent 3½ years

(Cl. D45—4)

To all whom it may concern:

Be it known that I, Samuel Fass, a citizen of the United States of America, residing in the Borough of Brooklyn, city of New York, county of Kings, and State of New York, have invented a new, original, and ornamental Design for a Watch Protector, of which the following is a specification, reference being had to the accompanying drawing, forming part thereof as shown:

Figure 1 is a perspective view of a watch protector showing my new design;

Figure 2 is a top plan view thereof;

Figures 3 and 4 are side and end elevational views, respectively, of the watch protector; and

Figure 5 is a cross section on the line 5—5 of Figure 2.

I claim:

The ornamental design for a watch protector, as shown.

SAMUEL FASS.
